UNITED STATES PATENT OFFICE.

DAVID W. EMMONS, OF NORTH ADAMS, MICHIGAN.

HAME-STRAP.

SPECIFICATION forming part of Letters Patent No. 308,068, dated November 18, 1884.

Application filed August 23, 1884. (No model.)

To all whom it may concern:

Be it known that I, D. W. EMMONS, a citizen of the United States, residing at North Adams, in the county of Hillsdale and State 5 of Michigan, have invented a new and useful Improvements in Hame-Straps, of which the following is a specification, reference being had to the accompanying drawings.

My invention relates to a strap for connecting the hames upon the collar of a horse, and it has for its object to provide a device of this character whereby the hames may be readily and quickly secured together, in which there can be no possibility of disengagement, and by 15 means of which the article is rendered lighter, requires less material, and can be constructed in a shorter time, and thus made cheaper in every respect.

The invention consists in the improved construction and combinations of parts hereinafter fully described, and pointed out in the claims.

In the drawings, Figure 1 is a perspective view of a hame-strap constructed in accordance with my invention. Fig. 2 is a longitudinal vertical section showing the notched section and the stop engaging one of said notches; and Fig. 3 is a detail view of parts detached.

In the accompanying drawings, in which like letters of reference indicate corresponding parts in all the figures, A represents my improved hame-strap, which consists of two sections, B and C. The outer ends of each of 25 these sections are bent to form a hook, *a*, adapted to fit a bail or loop, which is provided at the lower end of each of the hame-sections. The strap or section B has at suitable intervals upon its sides ears *b*, which are turned inwardly to form guides for the other strap or section, C, which slides therein. Near 35 its inner end the section B is provided with two upwardly-projecting lugs, *d*, in the upper ends of which is mounted a pin, *e*. Upon 40 this pin *e* is mounted a catch or stop, D, formed at its outer end with a finger-piece, *f*, which is weighted so that the tendency is to force the other end of this stop or catch upwardly. This other end is notched at *m m* on each side 45 to form an engaging nib, *g*, in the center, for the purpose which will be more fully explained. The section C, which is attached to

the adjacent hame, is cut upon its upper face to form notches *g'*, the rear walls of which are turned slightly upward.

In operation, the hames are placed upon the collar, and the sections composing the strap, as before mentioned, are hung upon or pivoted thereto. The section C, having the notches, is then slipped or slid between the 55 guides of the section B, and as soon as the desired adjustment is obtained the weighted catch is dropped (it being previously supported from engagement with the notches of the section C, while the same was being slid to the desired adjustment) and engages one of the notches, and will thus hold the sections composing the strap firmly and securely, and as the free end of the catch or stop is weighted there will be no liability of its detachment 60 from the section C.

To disengage the sections, it is only necessary to raise the weighted end of the stop, when the sections may be readily separated or disengaged.

It will be seen from the above description that a hame-strap constructed in accordance with my invention is simple, may be manufactured and supplied at a slight cost, and that its operation is certain and effective.

In order to define the scope and advantages of the present invention, I would have it understood that I am aware that it is not new to form a hame-fastener of two sliding adjustable sections, one of which is provided with a 75 series of teeth and the other carries a weighted catch, since the construction does not attain the objects of the present invention.

In the construction herein shown and described, for which I lay special claim, the article 80 is lighter, requires less material, can be constructed in a shorter time, and consequently made cheaper in every respect, so as to be brought within the reach of all.

It will be observed that the notched engaging-nib *g* of the weighted catch will enter one of the slots *g'* of the upper section and catch against the under side of the upturned wall of this slot, and by that means the weighted end will serve to bind the nib more tightly in position, and thus there can be no possibility of the catch becoming disengaged, as would be the case where an ordinary pawl and ratchet-teeth are used.

Having fully described my invention, what I claim as new, and desire to secure by Letters Patent, is—

The hame-fastener herein described, consisting of the two sliding sections B C, having inwardly-turned hooks *a a* at one end, ears *b*, formed at suitable intervals upon the sides of section B, and turned inward to form guides for the other section, C, the latter having notches *g* cut out of its upper face, the rear walls of which notches are turned slightly upward, lugs *d*, projecting upward from the section B, a pin, *e*, mounted in the lugs, and

a catch, D, mounted on the pin, one end of the catch mounted on the finger-piece *f*, which is weighted, as shown, and the other end notched to provide an engaging-nib, *g*, at the center, for the purpose set forth.

In testimony that I claim the foregoing as my own I have hereto affixed my signature in presence of two witnesses.

DAVID W. EMMONS.
